UNITED STATES PATENT OFFICE

143,642

DESIGN FOR AN ARCH SUPPORT

George N. Bouthillette, Everett, Mass.

Application April 4, 1944, Serial No. 113,132

Term of patent 14 years

(Cl. D7—5)

To all whom it may concern:

Be it known that I, George N. Bouthillette, a citizen of the United States, residing at Everett, in the county of Middlesex and State of Massachusetts, have invented a new, original, and ornamental Design for an Arch Support, of which the following is a specification, reference being had to the accompanying drawing, forming part thereof.

In the drawing:

Fig. 1 is a plan view of an arch support showing my new design;

Fig. 2 is an edge view looking to the right of Fig. 1; and

Fig. 3 is a sectional view on line 3—3 of Fig. 1.

My design for an arch support of the specific form as illustrated on the drawing is characterized by the shape and manner of the merging of the metatarsal and longitudinal cushions, in combination with the incline wedge-shaped side extension as seen most clearly in Fig. 3.

I claim:

The ornamental design for an arch support, substantially as shown and described.

GEORGE N. BOUTHILLETTE.
